UNITED STATES PATENT OFFICE.

ERIK HEYL, OF BUFFALO, NEW YORK.

DESIGN FOR A FLAG, PENNANT, EMBLEM, SIGN, OR ARTICLE OF A SIMILAR NATURE.

53,176.

Specification for Design.

Patented Apr. 8, 1919.

Application filed February 7, 1919. Serial No. 275,669. Term of patent 3½ years.

To all whom it may concern:

Be it known that I, ERIK HEYL, a citizen of the United States, residing at Buffalo, in the county of Erie and State of New York, have invented a new, original, and ornamental Design for a Flag, Pennant, Emblem, Sign, or Article of a Similar Nature, of which the following is a specification, reference being had to the accompanying drawing, forming part thereof.

The drawing is a face view of a flag embodying the design.

I claim:

The ornamental design for a flag, pennant, emblem, sign, or article of a similar nature, as shown.

ERIK HEYL.
